UNITED STATES PATENT OFFICE.

JOSEPH SCHNEIBLE, OF NEW YORK, N. Y.

COOLER OR CONDENSER.

SPECIFICATION forming part of Letters Patent No. 710,810, dated October 7, 1902.

Application filed August 8, 1900. Serial No. 26,217. (No model.)

To all whom it may concern:

Be it known that I, JOSEPH SCHNEIBLE, a citizen of the United States, residing in the borough of Manhattan, city of New York, State of New York, have invented certain new and useful Improvements in Coolers or Condensers, of which the following is a specification, reference being had to the accompanying drawings, forming a part hereof.

10 This invention relates to coolers or condensers of the general type commonly employed in breweries and in other places where the temperature of a flowing liquid is to be reduced by cold brine or an expanding gas or other cooling medium contained in pipes surrounding or inclosed in the pipes through which flows the liquid to be cooled or where a gas—such as ammonia, for example—is to be cooled and condensed.

20 The object of the invention is to improve generally the construction of such coolers or condensers.

One particular object is to provide for such a construction as will permit the parts to be 25 assembled readily, so that the manufacturer having the pipes in stock and the couplings therefor can set up on short notice a cooler or condenser of as many pipes as may be desired without occupying for a long time the 30 floor-space necessary for the erection of such coolers as they are usually constructed and will permit any pipe to be removed from a cooler when necessary for repair or for any other purpose without requiring the use of the 35 whole cooler to be discontinued pending such repair.

A further object is to provide for such a construction as will permit the cooler to be cleansed easily.

40 Still another object is to render less liable the development of leaks through the breaking of joints by unequal expansion of the parts if the cooler is subjected to high temperature, as in cleansing with hot water.

45 A further object is to prevent the escape of the cooling medium, in case of a leak in the pipes in which it is carried, into the pipes in which is carried the liquid to be cooled.

50 Other results accomplished by the invention will be referred to more particularly in the following description of the embodiment of the invention, which for purposes of explanation of the nature of the invention has

been chosen for illustration in the accompanying drawings, in which—

55 Figure 1 is a view in side elevation of a twelve-pipe cooler or condenser constructed in accordance with the invention. Fig. 2 is an end view of the lower portion of the cooler as seen from the left in Fig. 1, but on a larger 60 scale. Fig. 3 is a detailed plan view of the end of one of the sections of the cooler and the couplings, on a larger scale than Fig. 2. Fig. 4 is a vertical sectional view on the plane indicated by the line 4 4 of Fig. 3. Fig. 5 is 65 a vertical sectional view on the plane indicated by the line 5 5 of Fig. 4; and Fig. 6 is a horizontal sectional view on the plane indicated by the line 6 6 of Fig. 2, but on a larger scale.

70 In the construction represented in the drawings the pipes A, which are intended to carry the liquid to be cooled, are arranged centrally within the corresponding pipes B, which conduct the cooling medium; but it is obvious 75 that this arrangement of the pipes might be reversed, if so desired. The inner pipes A are longer than the outer pipes B, so that they project beyond the same at each end, and both are supported in a chambered casting or coupling-piece C at each end. One of the pipes, as B, is preferably threaded into the coupling-piece, as clearly shown in Fig. 4, the threaded joint being supplemented by a packed joint, preferably a lead joint c, the outer pipe communicating with the chamber c' within the coupling-piece. The inner pipe, as A, is extended through the chamber of the coupling-piece and through and beyond the outer wall of the coupling-piece with a packed 80 joint, preferably a lead joint, as at c'. By the prescribed arrangement of the pipes and their connection to the coupling-pieces the effect of longitudinal expansion of the inner pipe when the cooler is being cleansed with 85 hot water is reduced to a minimum, and should any leakage occur at the joint c' the gas or other cooling medium will escape into the air and will not escape into the inner pipe A, the joint between such inner pipe and the return-bend D, which connects such inner pipe with the next inner pipe above or below it, being formed wholly outside of the coupling-piece C. Each coupling-piece C rests upon a similar coupling-piece below it, or in case of the 90 lowermost pipe of the cooler upon a suitable 95 100 105

pedestal E, the adjacent faces of the castings or coupling-pieces being formed to fit closely upon one another, the castings being also formed with flanges c³ and c⁴ to receive bolts 5 c⁵ and c⁶, respectively, by which the castings are firmly secured together, so that the cooler or condenser may be made up of as many pipes as may be desired and so that if any 10 two pipes or sets of pipes are removed the pipes or sets of pipes above and below those removed can be firmly secured together. It will be understood that each inner pipe communicates at one end with the inner pipe below it and at the other end with the inner 15 pipe above it, while each outer pipe communicates at one end with the outer pipe below it and at the other end with the outer pipe above it. For the purpose of establishing communication between two adjacent outer pipes 20 each of the castings or coupling-pieces C is provided with a radial opening or mouth c⁷, and the chambers of the corresponding castings or coupling-pieces are carried to the meeting faces of the two castings, so that the 25 mouths of the two chambers shall register when the two castings are assembled, as clearly shown in Figs. 4 and 5, a packing c⁸ being interposed between the meeting edges, as indicated in Figs. 4 and 5, to insure a tight joint 30 when the bolts c⁶ are set up. It is obvious that the upper and lower castings or coupling-pieces of each pair may be precisely alike, the one being inverted with respect to the other. For the purpose of connecting adjacent inner pipes a return-bend D is provided 35 having at each end a seat d for the end of the corresponding pipe A. This return-bend is held firmly against the ends of the pipe to form a tight joint by link-bolts F, which may 40 be pivoted upon the bolts c⁶, and receive at their outer ends thumb-nuts f to engage slotted lugs d' on opposite sides of the elbow.

The upper and lower pipes A of the cooler are provided, respectively, with a coupling G 45 for connection with the pipes which deliver to the cooler the liquid to be cooled and conduct away the cool liquid. Such couplings may be held to the ends of the pipes A by substantially the same means as the return-bend D, as represented in Fig. 6. The uppermost coupling-piece C is preferably formed with a lateral connection H for the pipe which delivers the cooling medium, and the lowermost coupling-piece C may also be provided 55 with a lateral connection H' for the pipe which conducts away the cooling medium.

Should it be desired at any time to clean with a brush the interiors of the inner pipes A, the return-bend D can be removed readily 60 to permit the introduction of the brush by loosening the thumb-nuts f and disengaging the bolts F. If the removal of any pipe becomes necessary at any time, the removal of such pipe, together with the one above it or 65 the one below it, as the case may be, can be accomplished readily by removing the bolts c⁵ above and below the pair of pipes at one

end and the bolts c⁶ above and below the same pair of pipes at the other end. It will be understood, of course, that reference is had 70 here to the removal of the inner pipe and outer pipe of each set together. When the pipes have been removed, as described, the pipes above and below those removed are connected, as will be readily understood. 75

It will be evident that various changes in form and relative arrangement of the parts of the improved cooler or condenser may be made, the invention not being restricted to the precise form and relative arrangement 80 shown and described herein.

I claim as my invention—

1. In a cooler or condenser, a series of sets of pipes, each set comprising an inner and an outer pipe, a coupling-piece at one end of 85 each set of pipes, adapted to receive and support the pipes, having a radial opening or mouth, in communication with the outer pipe and having its opposite faces formed for contact with the next adjacent coupling-pieces, 90 each of the coupling-pieces being arranged with its radial opening or mouth in communication with the radial opening or mouth of an adjacent coupling-piece, and with its faces opposite the radial opening or mouth in contact with the corresponding face of an adjacent coupling-piece, means for detachably securing each of the coupling-pieces to one of the adjacent coupling-pieces and independent means for securing each of the coupling-pieces to the other of the adjacent coupling-pieces, whereby each of the coupling-pieces may be removed without affecting the other coupling-pieces; substantially as described. 95

2. In a cooler or condenser, a series of sets of pipes, each set comprising an inner and outer pipe, a coupling-piece at each end of each set of pipes, adapted to receive and support the pipes, having a radial opening or mouth in communication with the outer pipe and having its opposite faces formed for contact with the next adjacent coupling-pieces, flanges formed on the coupling-piece about the radial opening or mouth and flanges 110 formed about the face opposite the radial opening or mouth, means for securing the flanges about the radial opening or mouth of one coupling-piece to the corresponding flanges of an adjacent coupling-piece, and independent means for securing the flanges formed about the face opposite the radial opening or mouth to the corresponding flanges of an adjacent coupling-piece, whereby a single coupling-piece may be removed without 115 affecting the coupling-pieces of the other sets of the pipes; substantially as described. 120

This specification signed and witnessed this 20th day of July, A. D. 1900.

JOSEPH SCHNEIBLE.
